US0D1108229S

(12) **United States Design Patent** (10) **Patent No.:** **US D1,108,229 S**
(45) **Date of Patent:** **** Jan. 6, 2026**

(54) **PRUNING SCISSORS**

(71) Applicant: **Yantai Greenery Tools Co., Ltd.**,
Yantai (CN)

(72) Inventors: **Changlei Fan**, Yantai (CN); **Bo Yu**,
Yantai (CN); **Liang Yu**, Yantai (CN)

(73) Assignee: **Yantai Greenery Tools Co., Ltd.**,
Yantai (CN)

(**) Term: **15 Years**

(21) Appl. No.: **29/938,837**

(22) Filed: **Apr. 23, 2024**

(30) **Foreign Application Priority Data**

Oct. 27, 2023 (CN) 202330701204.8

(51) **LOC (15) Cl.** **08-03**

(52) **U.S. Cl.**
USPC **D8/5**

Assistant Examiner — Rene H. Kadoo

(57) **CLAIM**

The ornamental design for a pruning scissors, as shown and described.

DESCRIPTION

FIG. 1 is a front, right and top perspective view of a pruning scissors showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures illustrate portions of the pruning scissors that form no part of the claimed design.

1 Claim, 7 Drawing Sheets
